UNITED STATES PATENT OFFICE.

CLARENCE MORRIS WARNER, OF CAMBRIDGE, ILLINOIS.

VOTING-MACHINE

No. 872,704:

Specification of Letters Patent.

Patented Dec. 3, 1907.

Application filed February 21, 1907. Serial No. 358,678.

To all whom it may concern:

Be it known that I, CLARENCE M. WARNER, a citizen of the United States, residing at Cambridge, in the county of Henry and State of Illinois, have invented a new and useful Voting-Machine, of which the following is a specification.

This invention has reference to improvements in voting machines, and its object 10 is to produce a machine wherein a voter can press a key to register a vote for the candidate he desires, or vote the entire ticket at once, but in so doing will lock the machine against any other candidates for the same 15 offices.

The invention comprises means through which provision is made whereby a citizen may vote for a candidate whose name may not appear on the machine.

20 The invention also comprises means whereby a register of the number of voters is made, no matter for how many candidates the voter may express his choice.

The invention also comprises means 25 whereby the entire mechanism may be reset at one operation after a voter has expressed his choice, either by a person duly authorized for the purpose or by suitable connections to the door of the voting booth so that 30 when a voter leaves the booth the machine will be reset ready for the next voter.

The invention also comprises means whereby certain portions of the voting mechanism may be coupled to provide for the 35 different manner in which voting is practiced at different places.

The invention also comprises means whereby certain of the voting keys may be locked in an inoperative position without 40 affecting the operation of any of the other keys, so that the machine is adapted to be used for a number of candidates less than the total number of candidates for which the machine is designed.

45 The invention also comprises means under the control of authorized persons only for locking the machine in part or as a whole against action.

The invention also comprises means 50 whereby the portions of the voting machine constituting the top thereof may be readily removed for the changing of names, but this part of the machine is so constructed that these names cannot be changed by unauthorized persons.

The invention also comprises other features which, together with those already mentioned, will be fully understood from the following detailed description when taken in connection with the accompanying drawings 60 forming part of this specification, in which,—

Figure 1 is a top plan view of the improved voting machine, with a portion of the top broken away to disclose the interior, and other portions shown in section; Fig. 2 is a 65 longitudinal vertical section through the machine on a line adjacent to the several corresponding sections of the several tiers of names of candidates and the voting keys therefor; Fig. 3 is a cross section on the line 70 $x-x$ of Fig. 2 showing one only of the card receptacles for receiving the votes not named among the regular candidates; Fig. 4 is an end view of the machine adjacent to the locking device for the entire machine with 75 the end of the cabinet broken away to display the mechanism immediately adjacent thereto; Fig. 5 is a perspective view, partially in section and partially broken away, 80 of a portion of the top of the cabinet; Fig. 6 is a perspective view, partially broken away and partially in section, of one end of one of the key locking slides and adjacent parts; Figs. 7 and 8 are perspective views of the 85 transmitting key-operated slide bars; Fig. 9 is a detail view showing the locking mechanism for the devices used to lock or unlock the operating parts of the machine in whole or in part; Fig. 10 is a detail view on an enlarged 90 scale of a portion of the register and operating mechanism adjacent thereto, intended to record the number of voters using the machine; and Figs. 11 and 12 are detail views of the push-buttons or voting-key heads.

Referring to the drawings, there is shown 95 a rectangular, box-like structure 1 of metal or wood or both having its interior divided into a number of spaces by parallel longitudinal partitions 2 extending from end to end of the machine, and with the exception of the lower half of that portion of the machine reserved for votes for other than the regular candidates, these partitions extend from top to bottom of the machine. These partitions are sufficient in number to provide supports 100 for the operating mechanism to be hereinafter described, and while I prefer to construct the machine with such partitions it is quite evident that other means for supporting the voting mechanism may be used.

The top of the cabinet is so constructed that it may be removed in sections as desired. For this purpose there is provided at points suitably spaced from the ends of the cabinet and at other points intermediate of these end points compound cross-bars 3, the construction of which is best shown in Fig. 5. These bars are composed of a top plate 4, a bottom plate 5, and an intermediate plate 6 having a limited longitudinal movement between the plates 4 and 5. The top and bottom plates 4 and 5 are coupled together by bolts, screws or rivets 7 passing through longitudinal slots 8 in the intermediate plate 6 to permit and to limit the extent of longitudinal movement of the said plate 6. One longitudinal edge of the plates 4 and 5 extends beyond the corresponding edge of the plate 6, so that the two plates 20 constitute the side and bottom walls of a groove, while on the other longitudinal edge the plates are all flush except that there is provided a projecting tooth 9 on the intermediate plate 6. Along the median line of the cross-bar 3 are a number of perforations or passages 10 extending through all three portions of the bar, while the perforations 10 through the bar 6 are elongated into slots 11 of less diameter than the perforations. These 30 perforations and slots 10 and 11 perform a function which will hereinafter appear.

Between the several cross-bars 3 and also between those nearest the ends of the cabinet and the end walls of the cabinet are placed a series of cover sections 12, most clearly shown in Fig. 5. These cover sections are also composite in structure, consisting of top plates 13, bottom plates 14, and intermediate plates 15. The bottom plates 40 14 are continuous or unbroken except at the point 16 where they are notched to receive the projection or tooth 9 on the sliding member 6 of the bar 3. The upper plate 13 of each section 12 is provided with slots 17 arranged transversely of the plate but when the plate is in position these slots extend longitudinally of the top of the casing. The member 15 of each cover section 12 is divided into appropriate sections to act as spacing 50 blocks for the top and bottom plates 13 and 14, and these spacing blocks are omitted below the slots 17. Space is therefore provided for the insertion of card or name-plates containing the names of candidates to be voted for and these names will show through the slots 17. When the slotted top sections of the cover are removed these names may be changed, and since when these sections are in place they are locked, only authorized persons can change the name-cards or plates. Suitable securing bolts or rivets 18 are employed to fasten the members of each cover section 12 together. The description of these top sections thus far given does 5 not, however, apply to the top section pro-

vided for the casting of votes for candidates whose names do not appear on the machine. The difference is that in these particular top sections there are other slots 19 in the bottom of the plate 14 immediately below the slots 17 in the top plate 13, and in these particular sections the slots 17 and 19 are somewhat differently shaped and are of less width than the slots 17 in the other sections. The purpose of these slots will appear further on. 75

One longitudinal edge of each top section 12 is formed with a tongue 20 made by slightly projecting the member 15 beyond the corresponding edges of the plates 13 and 14 of the section. The top of the casing is 80 assembled by introducing the tongue 20 of a section 12 into the corresponding groove formed along the edge of one of the bars 3, while the other edge of the section is lowered until the tooth or projection 9 passes through 85 the notch 16 in the bottom plate 14, it being assumed that at this time the plate 6 has been moved in the appropriate direction to the full extent of its travel. When the section 12 has been lowered sufficiently to cause 90 the tooth 9 to engage under the upper projecting wall of the plate 13 it will hold the section 12 from further downward movement. The notch 16 is at one end of a space between two contiguous spacing members 15 95 of a section 12, and is only about one-half the width of that space, so that the member 6 of the bar 3 may be moved in a direction to cause the tooth 9 to become lodged between the plates 13 and 14 and thus lock the top 100 section 12 from removal.

The sliding member 6 of the cross-bar 3 projects beyond the edge of the casing to provide a manipulating end 21 by which it may be moved longitudinally when desired, but in 105 order to prevent any unauthorized manipulation of this sliding member 6 there is provided on the inside of the casing a suitable lock 22, the bolt 23 of which may be moved into a suitable perforation in the plate 6 110 through a corresponding perforation in the plate 5. This perforation is so situated that the bar may be locked when moved to its innermost position between the plates 4 and 5. The lock 23 may be reached by a suitable key 115 through a keyhole 24.

In order to fasten the bars 3 securely in place, there are provided bolts 25 passing through suitable perforations in the plates 4 and 5 and the slots 8 in the plate 6. These 120 bolts which may, if desired, replace some or all of the bolts or screws 7 before mentioned, extend down alongside of the partitions 2 and have one end 26 turned at an angle to enter suitable perforations in said partitions 125 in order to engage the same and thereby lock the cross-bars 3 firmly in place.

Directly beneath the perforations 10 in each bar 3 there is a vertically-moving sliding bar 27, the upper end of which is formed with 130

an elongated socket 28 and near the lower end of which the bar is formed with a head 29 having two approaching beveled faces 30—31 at its lower end merging into a downwardly-extending stem 32. The bar may be supported for longitudinal movement in appropriate brackets on the partitions 2, and its upper socket end 28 is of such size as to receive the cylindrical end 33 of a push-button 34, the stem 35 of which is of less diameter than the end 33. The diameter of the cylindrical end 33 is such that it will pass through the perforations 10 in the three members of the bar 3 when the perforations therein are 5 coincident, but the slots 11 are of such width as to prevent the passage of the cylindrical ends 33 of the push-buttons through them, but will permit the passage of the smaller stems 35. It will thus be seen that when a 10 push-button has been introduced through a perforation 10 and seated in a socketed end 28 of a bar 27 and the sliding member 6 has been pushed in the proper direction to cause the walls of the slot 11 to straddle the stem 35 of 15 the push button, the latter is securely locked against removal but may have a limited movement equal to the distance between the head 34 and the top of the cross-bar 3. This 20 distance is ordinarily sufficient to operate the mechanism controlled by the bar 27, but for certain purpose, which will hereinafter appear, I may use push-buttons 36 having stems 35 so short that the movement of the push-button is practically eliminated. The 25 cylindrical portions 33 of the push-buttons are not fastened in the sockets 28 so that when a short-stem push-button is used, the push-bar 27 may move to the extent of its longitudinal travel without the push-button 30 itself moving. The push-button constitutes a guide for the upper end of the push-bar 27. It will be seen that by making the perforations 10 in all the bars 3 alike and the slots 11 in all the plates 6 alike these long and short 35 push-buttons may be interchangeable as desired and the purpose of this interchangeability will appear further on.

In each compartment between the partitions 2 near the bottom thereof and bridging the spaces between the bars 27 are sliding frames 37 and 38, the frames 38 being similar to the frames 37 except that they are shorter. The frames 37 are best shown in Fig. 7 and the frames 38 are best shown in Fig. 8. 40 These frames 37 and 38 are rectangular in shape consisting of two side bars, as shown, with a central cross-bar, or more, if necessary, and two beveled end cross-bars 39—40. The side bars of the frame 37 are extended beyond the cross-bar 39, as shown at 41. The several frames 37 and 38 in each compartment formed by the partitions 2 are supported at their ends by brackets 42 fast on the partitions 2 in such manner that these frames 45 may slide longitudinally in the brackets, and

the said frames are so placed that the ends 41 of one frame will abut against the beveled end-bar 40 of the next adjacent frame, but the frame 38 is located at the end of the series and has no abutting extensions 41. The 50 ends 41 of the frames 37 are of such length that the contiguous beveled surfaces of the end-bars 39 and 40 of two abutting frames are spaced apart a greater distance than the distance between the beveled faces 30 and 31 55 of the head 29 of a bar 27, the head 29 being in normal position so located that its beveled face 30 is in contact with the beveled face of the end-bar 40 of a frame 37, so that when the bar 27 is pushed downward by the proper manipulation of the push-button or head 34 the reaction between the beveled faces 30 and 40 will cause the corresponding frame 37 to move longitudinally in the brackets 42, and since the ends 41 of each frame 37 are in 60 contact with the next adjacent frame 37 or 38 all those frames in advance of the particular frame 37 under consideration will participate in this movement. It will be understood, of course, that suitable brackets may 65 also serve to guide the lower ends of the sliding or push-bars 27. The push-bars 27, therefore, may be entirely supported and guided by such brackets at the lower end and the stems 33 of the push buttons 34 at the 70 upper end, although this does not preclude the use of other supporting means for the push-bars 27 if such be desirable.

The push-bar 27 adjacent to the section of the machine reserved for votes for candidates not named on the machine has one-half of the head 29 omitted and this head is provided with the beveled face 30 only, since there is no frame 37 beyond it. Upon each 75 push-bar 27 adjacent to the name of a candidate there is provided a short distance above the head 29 a laterally-projecting lug 43 engaged on its upper face by the ball-head 44 of a rocker arm 45 fast on a rock shaft 46 extending laterally through the 80 several compartments and beyond the side of the machine to which a voter is admitted where it contains a crank 47 and handle 48, so that should the voter desire to vote a 85 straight party ticket he need only move the handle 48 and the crank 47 through a sufficient arc to cause all the rocker arms 45 to engage the lugs 43 of all the push-bars 27 corresponding to the entire party ticket. As 90 will hereinafter appear, this will cause the 95 registering of one vote each for all the party nominees whose names are found in the list of candidates under the head of that particular political party. Now, in order to provide for the registering of the vote indicated by 100 the voter either by the movement of the crank 47 or by the individual depression of the push buttons 34, there is provided a registering apparatus which I will now proceed to describe. Near the upper section of the 105

casing and in each space adjacent to the push-buttons 34, corresponding to the candidates names there is a transverse shaft 49 which may be simply a fixed bar passing through 5 the sides of the casing and there receiving nuts 50 so that the bar serves as a means for bracing and securing the sides of the casing together. Upon this bar, in the spaces between the partitions and beneath the candidates names but not beneath the party name 10 is a large toothed wheel 51 having ratchet teeth 52 on its periphery and also formed with a laterally-projecting drum 53 terminating at the end remote from the ratchet wheel 15 51 in another ratchet wheel 54 of smaller diameter than the ratchet wheel 51 and having its teeth disposed in the opposite direction.

On one side face of the ratchet wheel 51 20 and overhanging the drum 53 is a continuous annular series of large teeth 55, each of which is provided with a definite number of smaller teeth. In practice the smaller teeth will be ten in number for each larger tooth, and 25 there will be as many as desired of these larger teeth on the ratchet wheel 51, so that by means of a registering device to be herein-after referred to the number of times the toothed wheel 51 is moved a distance of one 30 tooth will be automatically recorded in multiples of ten, with the individual numbers less than ten less prominently recorded, whereby the tabulation of the vote will be greatly simplified. The means for actuating 35 these registering devices is as follows. There is a link 56 fast at the point 57 to the corresponding partition 2, and the other end of this link is slotted, as shown at 58, to receive a pin 59 fast on the adjacent push-bar 40 27. The link 56 carries a pawl 60 having a head 61 so shaped as to engage the teeth of the ratchet wheel 54 in a manner to pull the ratchet wheel 51 upon its axis counter-clockwise as viewed in Fig. 2. This will occur 45 whenever the push-bar 27 is depressed. The pawl 60 is maintained in operative relation to the teeth of the ratchet wheel 54 by a suitable spring 62. Carried by each push-bar 27 is another pawl 63 in engagement with the 50 teeth 52 on the periphery of the ratchet wheel 51 and so located as to tend to prevent the rotation of the ratchet wheel 51 in the direction in which it is impelled by the pawl 60. The pawl 63 moves up and down with 55 the push-bar 27, and immediately beneath the end of the pawl where it engages the teeth 52 is an upright fixed plate 64 fast on one of the partitions 2, and also overhanging the top of the pawl at a point close to its 60 point of engagement with the teeth 52 is another fixed plate 65 curved around the pivotal end of the pawl and extended downward for a distance, thence laterally, and finally joining the plate 64 to which it may 65 be riveted or otherwise secured so that the

plate 65 is also fixed against movement. The plates 64 and 65 constitute a guiding cage for the pawl 63, so that when the bar 27 is depressed the pawl is immediately drawn into the space between the plates 64 and 65 by the engagement of the plate 64 with its free end. When the bar 27 is moved upwardly the free end of the pawl engages the curved overhanging portion of the plate 65 and is guided to and through a throat 70 formed by the contiguous ends of the plates 64 and 65 and is directed into engagement with a tooth 52 on the ratchet wheel 51. Therefore, when a bar 27 is depressed, the pawl 63 is immediately disengaged from the 75 teeth 52, leaving the ratchet wheel 51 free to be rotated by the pawl 60, and as soon as the push-bar 27 is elevated again this wheel is locked against further rotation by the pawl 63. The cage formed by the plates 64 and 65 renders it unnecessary to have a spring to 80 actuate the pawl 63, and thus a weak element, namely, a spring, is in this particular instance avoided. Now, suppose a voter 85 shall depress one of the keys 34. It will be seen that the ratchet wheel will be rotated a 90 distance of one tooth but at the same time the beveled face 30 on the head 29 engages a beveled end-bar 40 of the frame 37 and the result is that the frame 37 is moved longitudinally toward the next push-bar 27 and its beveled end-bar 39 will abut against the beveled face 31 of the next adjacent push-bar 27, thus locking the same against downward movement, while the extensions 41 of the 95 same frame 37 will engage and push the next succeeding frame 37 into like locking position for the next succeeding push-bar 27, and so on throughout the whole series until finally the end frame 38 of the series is also pushed 100 longitudinally a like distance.

Upon each push-bar 27 on the side opposite the lug 43 but near to the latter is another lug 66 in the path of which as it moves downward is a ball-head 67 of a rock arm 68 fast on a rock shaft 69 extending laterally through the partitions 2. Fast on this rock shaft 69 in the chamber between the last partition 2 and the side of the casing nearest to the voter is an angle arm 70 extending upward to a point adjacent to the transverse shaft 49, which latter will serve as a stop for the arm 70 during one phase of its movement. At the upper end the arm 70 is pivotally connected to a bar 71 extending longitudinally 110 through the machine for a sufficient distance to connect all the arms 70 fast on all the rock shafts 69 located in the machine, there being one rock shaft 69 for each longitudinal series of push-bars 27. This arrangement is provided so that when any one of the push-bars 27 is depressed the entire series of rock shafts 69 will be moved on their axes.

Located in the compartment between the partition 2 and the side of the casing remote 115

from the voter is another counter consisting of a ratchet wheel 51 with its drum 53, ratchet wheel 54 and pawls 60 and 63, all as before described. In operative relation to this counter or register is a push-bar 27 which I may term a dummy push-bar since it is not under the control of a push-button 34. This push-bar 27 is provided with a lug 66, as before, and another opposing lug 72 adjacent to but spaced therefrom, and between these two lugs engages the bail-head 73 of a rock-arm 74 fast on the last rock shaft 69 at the end of the machine remote from that end reserved for the casting of votes for candidates whose names do not appear upon the machine. Now, when any one of the push-buttons is depressed by a voter and the push-bars 27 likewise depressed, thus actuating the connected series of rock shafts as before described, the arm 74 through its head 73 will engage the lug 72 on the dummy push-bar 27 and thereby actuate the additional register by one tooth. When once actuated this register cannot again be actuated until the machine is once more set for a new voter, since the pushing down of one push-bar 27 has carried all the arms 68 out of engagement with the lugs 66 on all the other push-bars 27 and all these push-bars are therefore inactive so far as this one particular register is concerned. This register therefore constitutes a means for recording the number of voters who have used the machine, since it can be actuated but once by each voter and immediately becomes inactive no matter how many other push-buttons 34 the voter may manipulate.

In order to produce a record of the vote cast that may be easily read so as to facilitate the tabulation of the vote, there is provided for each register a reel 75 containing a paper or other suitable strip. Each reel is hung in brackets 76 fast on the partitions 2, or, in the case of the voter register, upon the partitions 2 and the side of the casing adjacent thereto. The paper or other strip upon this reel has its end secured to the drum 53 by a clip 77 so as to rotate with said drum. Pivoted to an adjacent partition 2 or the side of the casing, as the case may be, is an angle-bracket 78, the free end of which is formed into an eye 79 for the reception of a pencil point 80 arranged to bear upon the strip coming from the reel 75. Pivoted to the bracket 78 is a spring arm 81 having a part arranged to bear upon the pencil and terminating in an upturned finger 82 arranged to be engaged by one of the cover sections 12 when in place on the machine, so that the spring arm 81 will maintain the pencil point in contact with the recording strip with a yielding pressure which provides a means for taking up the wear on the pencil point. Upon the end of the pivoted bracket 78 is formed a tooth 83 arranged to engage

the smaller teeth formed on the large teeth 55 overhanging the drum 53. The bracket 78 is made of spring metal so that the pencil point may be moved laterally as it is engaged by the large teeth 55 and also by the smaller teeth thereon. The smaller teeth correspond in number to the teeth on the ratchet wheel 54 so that they indicate the number of times that the register has been actuated, and the larger teeth are multiples of the smaller teeth, preferably embracing ten of the smaller teeth, and, for convenience, it is desirable that one complete rotation of the register should correspond to one hundred actuations thereof. Now, in order to provide a means for indicating the number of times each register has been completely rotated, there is provided a bracket 84 upon which is journaled a disk 85 provided with a number of laterally projecting studs 86 arranged for engagement with a stop 87 on one side of the ratchet wheel 51, so that at each rotation of the latter the stop 87 will engage one of the studs 86 and move it a definite distance which will agree to, say, one hundred votes. In order that the registering disk 85 may be read easily, the bracket 84 is provided with a pointing finger 88.

For the purpose of resetting the machine when the voter has finished his voting, the shaft 69, shown at the left in Figs. 1 and 2, is provided outside of the casing on the side remote from that to which the voter is admitted and within reach of an authorized person, say, one of the judges, with a manipulating handle 89. By properly turning the shaft 69 all the several push-bars 27 that have been depressed will, by means of the connecting bar 71, the several arms 70 and the rock arms 68, be lifted to operative position. At the same time other rock arms 90 fast on the rock shaft 69 carrying the manipulating handle 89 will engage by their ball-heads 91 the center cross-piece of all the sliding frames 38 and through them will cause the longitudinal movement of all the sliding frames 37 to their original position, so that the machine is again ready for another voter.

When a less number of candidates are to be voted for than that for which the machine is designed, provision is made for locking out of operation those longitudinal lines of push-bars which will correspond to the offices for which there are no candidates. For this purpose there is arranged at the left-hand end of the machine, as viewed in Figs. 1 and 2, a cross-bar 92 extending across the machine adjacent to the ends of the sliding frames 38 nearest the corresponding end of the casing. Attached to this cross-bar are a number of sliding blocks 93 having their lower ends beveled, as shown at 94, and fast on the cross-bar 92 by means of screws 95 passing through slots 96 in said blocks 93. The construction is such that the blocks 93

may be adjusted vertically with relation to the bar 92 so that when this bar is moved vertically, as will hereinafter appear, the beveled faces 94 of the blocks 93 may be carried below the corresponding beveled faces 41 of the frames 38 and the body of the block be brought into the path of these frames 38, thus locking them against movement toward the contiguous end partition of the casing. 5

10 At the same time others of these blocks 93 may be so adjusted that when the bar 92 is lowered they will remain out of the path of the beveled faces 41 of the frames 38. In order to readily reach the adjusting screws 95 15 whereby the vertical position of the blocks 93 may be determined, the corresponding end of the casing is provided with a slot 124 covered by a plate 125 secured to the casing by suitable screws. At intervals the cross-bar 20 92 is provided with vertically extending guide arms 97 having retaining brackets 98 fast to the end of the casing so that this bar, together with its guide arms, is free to move vertically. Each guide arm 97, of which 25 there is usually arranged one for each six compartments more or less, is provided with two parallel laterally extending arms 99 between which is located a cam 100 mounted on a shaft 101 passing through the several 30 partitions 2 and out through the side of the casing remote from that to which the voter is admitted. Outside the casing the shaft 101 has fast thereon a spring manipulating arm 102, the end 103 of which is formed into 35 a tooth engaging notches 104 in the casing, which notches are best shown in Fig. 9. This permits the arm 102 to be moved in a direction to rotate the shaft 101, and the finger 103 will when over a notch 104 spring 40 therein and so hold the shaft from rotation except when sufficient force is exerted to overcome the force of its resiliency, and cause it to ride out of the notch. Within the casing the shaft 101 is provided with a notched 45 disk 105 arranged to be engaged by a bolt 106 which can only be reached by an authorized person. Thus the machine may be set to operate for any desired number of candidates within the capacity of the machine and 50 those spaces which are not used are locked against manipulation. It will be understood, of course, that the push-buttons 34 of those push-bars 27 which are locked out of operation will be replaced by push-buttons 55 36 which, as before explained, are inoperative to the voter.

The operation of the machine has been described in part and will be apparent from the foregoing description. Assuming that the 60 machine is ready for a voter, the latter enters the booth where the machine is and if he wishes to vote a straight party ticket he turns the proper crank 47 which will register one vote each for all the candidates under 65 the party name. Should, however, he de-

sire to vote fraudulently, he will find all the other push-buttons locked against further manipulation. Should the voter desire to split his ticket, he may push a button for any candidate he pleases. This will at once lock the push-buttons for all other candidates in the same longitudinal line, which are candidates for the same office. He may then push any button in any other line he pleases and this will lock all the other buttons in that longitudinal line, and so on. He may vote for any candidates he pleases so long as he votes for but one candidate in any one longitudinal line. If he attempts to vote any push button not having a name opposite it, 70 he will find that push-button inoperative because in such place there is a short push-button. This short push-button is provided simply to prevent a voter from being confused by finding an operative push-button 75 opposite a space where no candidate's name appears, and he is therefore prevented from casting a blank vote. When the voter leaves the booth the judge will turn the handle 89 and reset the machine, or this may be 80 done automatically. For instance, the handle 89 on the shaft 69 may be connected to the door of the booth by suitable mechanism indicated by the link 126 in Fig. 1, so that when the door is opened the machine is set, 85 or a platform upon which the voter stands may be provided and connected to this handle so that when the voter leaves the platform the machine is set, or even when the voter first steps on the platform the machine 90 may be set. In fact, any automatic means for the purpose may be provided if so desired.

Provision is made at one end of the machine for the casting of votes for persons 105 whose names do not appear upon the machine and which may be designated "irregular" votes, meaning simply that the votes are not those for regular party nominees. The irregular vote receptacles are shown at 110 the right-hand end of the machine, as viewed in Figs. 1 and 2. At this point the cover section 12 is provided with the contiguous slots 17 and 19 passing entirely therethrough and beneath each of these slots is located a 115 flat narrow chute 107 having its upper end flaring and provided with a lateral lip, as shown at 108, and located close beneath the lower slot 19 in the cover section 12. This chute 107 is open at the lower end but 120 under normal conditions this lower end is closed by a fixed plate 109 fast on one of the partitions 2. The chute 107 is provided about midway of its vertical height with trunnions 110 journaled in brackets 111 fast 125 on one of the partitions 2, the arrangement being such that this chute 107 may be turned on its trunnions to carry its end 108 out of line with the slots 17 and 19. Near the lower end each chute carries an angle bracket 130

112 having a slot 113 arranged at an angle to the vertical, and in this slot there engages a pin 114 fast on a bracket 115 carried by the push-bar 27 arranged to operate this particular chute 107 now being described. Now, when a voter desires to cast an "irregular" vote, he depresses the push-bar adjacent to the slot in the cover section 12, and in the line of the office for which he desires to vote. 10 This tilts the chute 107 until the opening in the top of the chute is in alignment with and immediately beneath the slots 17 and 19. Then the voter inserts a card upon which is written or printed the name of the person he 15 wishes to vote for; but which name is not found among those of the regularly nominated candidates displayed on the machine. The card or vote falls through the chute 107 until arrested by the plate 109. The depression 20 of the push-button 34 corresponding to the vote just cast will lock the push-buttons of all of the regularly named candidates for the same office, so that the voter is prevented from voting for any of the regularly named 25 candidates for the same office if he casts his vote for one of those not named on the machine. When the machine is reset the chute 107 is turned upon its trunions until the upper end is out of alignment with the slots 17 30 and 19 and the lower end has been carried away from the plate 109, thus permitting the card or vote to fall into the corresponding compartment of the box or drawer 116 located beneath the several chutes 107.

35 The push-bars 27 provided for the irregular votes have threaded bosses 117 so arranged that two or more of them may be attached together by a plate or bar to provide for the cumulative voting prevalent in some places, 40 so that anyone desiring to vote through the card chutes under the cumulative system, where the latter is prevalent, can vote in any one of the card chutes and the others will all be locked at the same time. For instance, 45 in the State of Illinois cumulative voting for Representatives is in vogue, and all the card chutes which agree to the Representatives will be locked together by means of the bosses 117, so that while any one of the 50 chutes provided for the Representatives may be used to cast the vote, all the other chutes connected thereto will be locked against further manipulation when the one has been used. The box or drawer 116 is introduced below 55 the chutes 107 through a door 118 hinged at its upper edge to the corresponding end of the casing, as shown at 119, and this drawer is provided at its ends with inwardly projecting wings 120 through which and through 60 the various partitions of the box or drawer may be passed a rod 121 having a head 122 at one end and at the other end perforated for the reception of a lock 123, so that this drawer may be securely locked in the casing 65 against unauthorized removal.

I claim:

1. In a voting machine, a register for the number of voters; a plurality of means, under the control of the voters, each connected to said register, and means whereby the first 70 means actuated by a voter throws the register out of connection with all the other means controlled by the voters.
2. In a voting machine, a register for the number of voters, push-buttons or keys for 75 the several candidates to be voted for, connections between the push-buttons or keys and the register of the number of voters, and means whereby the movement of the first push-button or key operated by a voter 80 throws the register out of connection with all the other push-buttons or keys.
3. In a voting machine, a register for the number of voters, a pawl-and-ratchet mechanism for moving said register step-by-step, 85 interconnected rock arms operating said pawl-and-ratchet mechanism, push-bars, one for each of the several candidates to be voted for, and means on each push-bar for engaging the rock arms and moving all the rock 90 arms simultaneously.
4. In a voting machine, push-bars under the control of voters, lugs thereon, rock arms in the paths of the lugs when the push-bars are depressed, rock shafts carrying the 95 rock arms, other arms on the shafts, a common connecting bar for all of the rock arms, a register for the number of voters, and a pawl-and-ratchet actuating means for said register. 100
5. In a voting machine, longitudinally moving push-bars, one for each candidate to be voted for and under the control of the voter, a rock arm in the path of each push-bar on its movement in one direction, connections between all the rock arms for simultaneous movement thereof, and means for moving the rock arms in the reverse direction for resetting the operating push-bars. 105
6. In a voting machine, push-bars, one for 110 each of the several candidates to be voted for and under the control of the voter, sliding members operated by each series of push-bars corresponding to an office to be voted for, means whereby the manipulation of any 115 one push-bar of a series locks all the other push-bars in that series, rock arms engaged by each push-bar, interconnecting means for the rock arms whereby the movement of any one rock arm through a push-bar moves all 120 the other rock arms out of engagement with the push-bars, other rock arms, one in operative relation to each series of sliding members, and means for the simultaneous operation of all the rock arms to move them to the 125 initial position and also to return the sliding members to the initial position.
7. In a voting machine, voting-keys and push-bars controlled thereby arranged in tiers to represent the candidates to be voted 130

for and the corresponding voting-keys of each tier constituting a longitudinal series to correspond to the office to be voted for, rock shafts having their axes parallel with the 5 tiers of keys, rock arms fast on said shafts and normally engaging the lugs or offsets on said keys and operated thereby, another arm fast on each shaft, a common connection for all these last-named arms, series of sliding 10 members, one series for each series of voting-keys corresponding to an office to be voted for, other rock arms on one only of the rock shafts and each arranged in operative relation to the series of sliding members, and 15 means for simultaneously moving all the rock arms to the initial position.

8. In a voting machine, a number of longitudinal series of voting-keys and push-bars corresponding to the offices to be voted for, 20 a coacting series of sliding members under the control of any one key of a series and locked against movement by the operation of any one key, sliding blocks simultaneously movable into the paths of the series of sliding 25 members and each block being independently adjustable to a position to maintain it out of the path of the sliding members when the unadjusted blocks are movable into the paths of these members, a common support 30 for all the sliding blocks, a series of cams engaging the common support at two or more points, a shaft for the cams, and means for rotating the shaft whereby the block support will have the same extent of movement 35 throughout its length under the action of the cams.

9. In a voting machine, a number of longitudinal series of voting keys and push-bars corresponding to the offices to be voted for, 40 a coacting series of sliding members under the control of any one key of a series and locked against movement by the operation of any one key, sliding blocks simultaneously movable into the paths of the series of sliding 45 members and each block being independently adjustable to a position to maintain it out of the path of the sliding members when the unadjusted blocks are movable into the paths of these members, a common support 50 for all the sliding blocks, a series of cams engaging the common support at two or more points, a shaft for the cams, and means for rotating the shaft comprising a spring arm and a circular series of notches or seats for 55 the spring end of said arm whereby the shaft may be completely rotated but will be held at any predetermined point of rotation against accidental movement.

10. In a voting machine, a number of 60 longitudinal series of voting-keys and push-bars corresponding to the offices to be voted for, a coacting series of sliding members under the control of any one key of a series and locked against movement by the operation 65 of any one key, sliding blocks simul-

taneously movable into the paths of the series of sliding members and each block being independently adjustable to a position to maintain it out of the path of the sliding members when the unadjusted blocks are 70 movable into the paths of these members, a common support for all the sliding blocks, a series of cams engaging the common support at two or more points, a shaft for the cams, means for rotating the shaft comprising 75 a spring arm and a circular series of notches or seats for the spring end of said arm whereby the shaft may be completely rotated but will be held at any predetermined point of rotation against accidental 80 movement, and a lock for the shaft consisting of a notched disk rotating with said shaft and a fixed bolt movable into the notches.

11. In a voting machine, push bars for operating the voting mechanism, removable 85 keys for actuating the push bars, and other keys of shorter length than and interchangeable with the first named keys, whereby the active push bars may be rendered inactive.

12. In a voting machine, push-bars for 90 operating the voting mechanism and formed with sockets at their upper ends, push-buttons having portions adapted to said sockets, stems of less diameter than the sockets and heads of greater diameter than the stems, 95 and locking means embracing the stems for preventing the withdrawal of the portions of the push-buttons seated in the socketed ends of the push-bars.

13. In a voting machine, push-bars for 100 operating the voting mechanism and provided with sockets at their upper ends, headed push-buttons having enlarged portions fitted to said sockets and stems of smaller diameter connecting the enlarged 105 portions to the heads, and a sliding locking member having openings of different width to permit the passage of the enlarged portions of the push-buttons and to lock the same against withdrawal from the socketed 110 ends of the push-bars.

14. In a voting machine, push-bars for 115 operating the voting mechanism and provided with socketed ends, headed push-buttons having portions adapted to said socketed ends and seated therein and provided with stems of different lengths, and locking means for holding the push-buttons to the push-bars, the length of the stems of the push-buttons determining the extent of movement of said push-buttons.

15. In a voting machine, push-bars having socketed ends, push-buttons having portions adapted to said socketed ends and seated therein and having stems of less diameter than the portions seated in the push-bars, a fixed member arranged between the push-bars and the heads of the push-buttons and having perforations large enough to permit the passage therethrough of the larger por- 125 130

tions of the push-buttons seated in the push-bars, and a sliding member carried by said fixed member and having openings permitting the passage of the enlarged portions of the push-buttons and slots leading from said openings of less width than the openings but of sufficient width to permit the passage of the stems only of the push-buttons.

16. In a voting machine, voting-keys having heads at one end, enlarged portions at the other end and connecting stems of less diameter than the enlarged portions, means for locking the push-buttons against removal comprising a composite bar formed of top and bottom plates fixed to the machine and an intermediate sliding plate, the three plates having matching perforations large enough for the passage of the enlarged portions of the push-buttons and the sliding plate having slot extensions of the perforations large enough for the passage of the stems of the push-buttons but too small for the passage of the enlarged portions of the push-buttons, and a lock for engaging the sliding plate when the latter is in the position where the slotted portions engage the stems of the push-buttons.

17. In a voting machine, a top therefor composed of a series of fixed bars spaced apart and removable sections between these bars containing passages for the name-plates or cards and slots for exposing the names, and means for locking the name-carrying sections between the bars and closing the passages against the removal of the name-plates or cards.

18. In a voting machine, a top therefor having fixed bars spaced apart and composed of top and bottom fixed members and

an intermediate sliding member provided with a locking tongue on one side and coacting with the fixed members to form a groove along the other side of each bar, and removable sections composed of top and bottom members and an intermediate member coacting with the top and bottom members to form a tongue along one edge to fit the groove in the fixed bars and having on the other edge a seat for the locking tongue on the sliding member of the fixed bars.

19. In a voting machine, a top therefor having fixed bars spaced apart and composed of top and bottom fixed members and an intermediate sliding member provided with a locking tongue on one side and coacting with the fixed members to form a groove along the other side of each bar, and removable sections composed of top and bottom members and an intermediate member coacting with the top and bottom members to form a tongue along one edge to fit the groove in the fixed bars and having on the other edge a seat for the locking tongue on the sliding member of the fixed bars, the top member of the removable sections being provided with slots and the intermediate member being made in sections and omitted under the slots whereby receptacles are formed for the insertion of name-cards or plates readable through the slots.

In testimony that I claim the foregoing as my own, I have hereto affixed my signature in the presence of two witnesses.

CLARENCE MORRIS WARNER.
